FISHING LURE

Finn H. Magnus, Essex Fells, N. J.

Application April 1, 1955, Serial No. 35,320

Term of patent 14 years

(Cl. D31—4)

Fig. 1

I claim:

The ornamental design for a fishing lure, as shown.
